CLAIM

The ornamental design for a consumer product package with indicia, as shown and described.

DESCRIPTION

FIG. 1 is a front elevational view of a consumer product package with indicia; and,
FIG. 2 is a front elevational view of another consumer product package with indicia.

The dash-dash-dash lines are for the purpose of illustrating environmental structure and form no part of the claimed design. The dash-dot-dash lines define boundaries of the claimed design and form no part of the claimed design.
